(57) **CLAIM**

The ornamental design for a motor scooter, as shown and described.

DESCRIPTION

FIG. 1 is a front and right side perspective view of a motor scooter showing our new design;

FIG. 2 is a rear and left side perspective view thereof;

FIG. 3 is a front and left side perspective view thereof;

FIG. 4 is a rear and right side perspective view thereof;

FIG. 5 is a right side view thereof;

FIG. 6 is a left side view thereof;

FIG. 7 is a front view thereof;

FIG. 8 is a rear view thereof;

FIG. 9 is a top plan view thereof; and,

FIG. 10 is a bottom view thereof.

The portions of the drawings illustrated in broken lines are directed to the environment of the design and form no part of the claimed design.

1 Claim, 10 Drawing Sheets
